(57) **CLAIM**

An ornamental design for a seat-base extender, as shown and described.

DESCRIPTION

FIG. 1 is a perspective view showing the seat-base extender of the present invention;

FIG. 2 is a top plan view thereof;

FIG. 3 is a bottom plan view thereof;

FIG. 4 is a front elevation view thereof;

FIG. 5 is a back elevation view thereof;

FIG. 6 is a first side elevation view thereof;

FIG. 7 is a second side elevation view thereof; and,

FIG. 8 is another perspective view thereof, showing the seat-base extender as used in a vehicle.

The ornamental design which is claimed is shown in solid lines in the drawings. The consistent short broken lines shown in FIGS. 1-8 are for the purpose of illustrating portions of the seat-base extender that form no part of the claimed design. The broken lines, in the form of a long line followed by double short lines, shown in FIG. 8 excluding the seat-base extender, showing portions of a vehicle, represent the environment in which the design is used. Surface shading is shown in irregularly broken lines.

1 Claim, 8 Drawing Sheets
